UNITED STATES PATENT OFFICE.

BURWELL BOYKIN, JR., OF BEAUMONT, TEXAS.

STRAIGHTENING-MACHINE.

1,096,349.

Specification of Letters Patent.

Patented May 12, 1914.

Application filed November 19, 1913. Serial No. 801,899.

To all whom it may concern:

Be it known that I, BURWELL BOYKIN, Jr., a citizen of the United States, residing at Beaumont, in the county of Jefferson and State of Texas, have invented a new and useful Straightening-Machine, of which the following is a specification.

This invention relates to improvements in straightening machines.

10 An object of the present invention is to provide a machine which will straighten pipes, rails, and allied structures in an expeditious manner.

15 A further object is to provide a machine of the class named in which friction cone bearings are provided which may be brought into contact with a beveled friction wheel so that the latter may be driven in either a forward or reverse direction and which bevelled wheel frictionally drives a gear with a 20 threaded aperture extending therethrough and through which aperture extends a bending screw so that the bending screw may be advanced or retracted in a forcible manner 25 for the straightening of curved or bent structures.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the drawings accompanying this specification and forming a part thereof, the preferable form of my invention is illustrated, in which:

40 Figure 1 is a view in side elevation of my improved straightening machine. Fig. 2 is a top plan view thereof, and Fig. 3 is a view in rear elevation.

45 Referring to the drawings in which similar reference numerals designate analogous parts throughout the several views, a base is provided and includes the longitudinal beams 4 and a plurality of transverse beams 5 extending therebetween and which are bolted thereto. A transverse beam or block 5 extends between the longitudinal beams, is mortised therein as clearly illustrated in Fig. 1, and forms an abutment against which the 50 bent articles such as rails are placed which are to be straightened. In order to further

strengthen the transverse beam or abutment 5, the blocks 7 are rigidly secured to the beams 4 and contact with and hold against transverse shifting the said beam 5. A cross 60 strut 8 is mortised between the blocks 7 and beams 4 and extends therebetween to further insure the absolute rigidity of the entire structure. A cross strut 9 extends between the beams 4 at their rear extremities 65 and is mortised between the said beams and the holding blocks 10 which are mounted above and rigidly secured to the beams. A thrust beam 11 extends between the beams 4 and is mortised therein, and contacts with 70 the front faces or ends of the holding blocks 10. The thrust bearing 12 is rigidly secured to the thrust beam 11 and is provided with an opening 13 extending centrally therethrough and through which opening extends 75 the bending screw 14. The thrust beam is provided with the opening 15 extending therethrough, through which the bending screw may advance or retract. The bending screw is provided with the keyway 16 cut 80 therein and which is engaged by the spline 17 so that the bending screw while mounted for axial or longitudinal movement will be held against rotation. A bearing 18 illustrated by dotted lines in Fig. 1 is carried by 85 the transverse beam 19 and supports the forward portion of the bending screw and prevents the transverse shifting thereof.

A gear wheel 20 is provided with the threaded aperture 21 extending there- 90 through and which receives the bending screw 14 therethrough. The said gear is provided with the collars 22 which contact with the thrust bearing upon one side and with the bearing 18 upon the opposite side. 95 Thus when the gear is forcibly rotated, the gear being held against transverse shifting and the said bending screw being held against rotation, provides that the bending screw will be advanced or retracted according to the direction of rotation of the gear. 100

A superstructure is mounted upon and secured to the beams 11 and 18 and which superstructure includes the longitudinally extending beams 23 held in spaced relation 105 by the cross members or beams 24. The beams 24 carry the pillow blocks 25 which rotatably support the shaft 26. The shaft 26 is provided with the spur gear 27 rigidly secured thereto and which meshes with the 110 relatively larger spur gear 20. Suitable means are secured to the shaft 26 to pre-

vent the longitudinal shifting thereof but which being of the conventional form are not illustrated. The rear extremity of the shaft 26 is provided with a friction beveled wheel 28, which is driven by the cone frictional wheels 29—29, the latter being mounted upon opposite sides of the beveled wheel and rigidly secured to the power driven shaft 30. Suitable blocks 31 are secured to the beams 23 and which blocks support the pillow blocks or bearings 32 journaled in which and rotatably mounted thereby is the shaft 30. A set of loose and tight pulleys 33 are mounted upon the shaft 30 and by means of which the shaft 30 is forcibly rotated. The shaft 30 may slide in an axial direction to bring the cone wheels upon opposite sides of the beveled wheel into frictional engagement therewith to thus drive the beveled wheel in a forward or reverse direction, according to which of the cone wheels is in engagement therewith.

A strut bar 34 extends between the rear extremities of the beams 23 and projects beyond one of the same to form a supporting arm 35 to which the lever 36 is pivotally secured. The lever 36 is provided with the pivoted member 37 and collar 38 which latter engages the shaft 30 and is adapted to longitudinally shift the same by the shifting of the lever 36. Thus, when a bent article as illustrated in dotted lines at 6 is placed upon the beams 4 and in contact with the transverse abutment 5, it will be in the path of movement of the bending screw 14, which latter is provided with the rotatable end members or forms 39 secured to the front extremity thereof so that it will properly engage different sized pipes or allied structures of different cross sectional contours. The shaft 30 being power driven, a shifting of the lever 36 will bring one of the rotating cones into forcible contact with the beveled wheel 28 with the result that the said wheel and shaft 26 which is secured thereto, will be rotated in a given direction. The said motion will be imparted to the gear 20 through the intervention of the gear 27 which is in mesh therewith and secured to the shaft 26. The gear 20 being driven by power will either advance or retract the bending screw 14, according to the direction of rotation imparted to the said gear. Should the rotation be such that the bending screw will be advanced, the latter will come forcibly in contact with the bent article and will tend to straighten the same by forcing it into contact with the abutment 5, the edge of which is formed as a plane surface. The reaction produced by the forcible contact of the bending screw with the bent article is transmitted to the

spur gear 20 and which in turn reacts upon the thrust bearing 12 which is preferably an anti-friction ball bearing and which being rigidly secured to the thrust beam 11, will successfully withstand the strain. The thrust beam 11 being supported against shifting by the thrust blocks 10 and being bolted as well as mortised to the longitudinal beams 4, will be sufficiently strong to withstand any stresses which may be brought to bear thereupon in the ordinary use of the machine. The fact that the cones 29 rely upon friction to drive the beveled wheel 28 forms a safety arrangement so that when the article is entirely straightened and is in rigid contact with the abutment 5, the increased thrust upon the beam 11 will be prevented from rising to excessive values by a slipping of the cones and beveled wheel. Thus there will be no disastrous results accruing when the bending screw comes into forcible contact with the transverse abutment 5.

Having thus described my invention, what I claim is:—

A straightening machine comprising a base, a transverse abutment with a plane side secured thereto, a bending screw mounted for sliding motion upon said base, means engaging said bending screw preventing the rotation thereof, a gear wheel provided with a threaded aperture extending therethrough mounted upon said bending screw, means for preventing the shifting of said gear wheel longitudinally of the said base, said means including an anti-friction thrust bearing, a superstructure carried by said base, a shaft rotatably mounted by said superstructure, a gear wheel carried by said shaft and meshing with the aforementioned gear wheel, a beveled friction wheel carried by said shaft, a shaft extending at right angles to the aforementioned shaft, two oppositely disposed cone friction wheels rigidly carried by said shaft and adapted to contact with the said beveled wheel upon opposite sides thereof, means carried by said last mentioned shaft for imparting rotation thereto, and a lever pivotally carried by said superstructure engaging said cone wheel carrying shaft adapted to shift the same in an opposite direction to bring one of the said cone wheels into contact with the beveled wheel and to move the other of said cone wheels out of contact therewith.

In testimony that I claim the foregoing as my own, I have hereto affixed my signature in the presence of two witnesses.

BURWELL BOYKIN, Jr.
